FOUNDRY FLASK

Anthony J. Klimek, Terre Haute, Ind.

Application January 10, 1950, Serial No. 137,809

2 Claims. (Cl. 22—107)

1

This invention relates to improvements in foundry flasks.

An object of the invention is the provision of a corner hinge construction for a snap flask in which the hinged ends of a pair of right angularly disposed walls of the flask are sheared off at an angle of 45 degrees with the sheared faces having interfitting stepped portions to afford rigidity to the structure, as well as to eliminate any tendency of twisting between the sections of the flask, a vertical slot being cut into each face of the inner edge thereof to receive an end of a flexible member which cooperates with the interfitting stepped portion to eliminate escape of sand at the hinge.

Another object of the invention is the provision of a closing means for the abutting ends of a pair of the walls, the abutting ends being diagonally opposite the hinged ends and movable away from each other to release the flask from the mold, the abutting ends having complementary interengaging means for retaining said ends in rigid relation with each other when locked together.

A further object of the invention is the provision of a sturdy and rigid flask in which pairs of walls are secured firmly together to form two sections with the walls of each section being at right angles to each other, each pair of the abutting ends of the flask having complementary interfitting grooves and ribs with a hinge connecting one pair of abutting ends together and an improved form of latching means removably connecting the other pair of abutting ends together.

A further object of the invention is the provision of a sturdy and durable snap flask having means at one corner for opening or closing the abutting ends and for retaining the ends open or closed, said ends being formed with interfitting members for guiding said ends into rigid relation with plates at the movable elements of the flask formed of materials of high wear resistance to limit wear to a minimum.

This invention is best understood from a consideration of the following detailed description taken in conjunction with the accompanying drawings, nevertheless, it must be borne in mind that the invention is not limited to the disclosure, but is susceptible of such changes and modifications as shall define no material departure from the salient features of the invention as expressed in the appended claims.

In the drawings:

Figure 1 is a view in perspective of my improved flask.

Figure 2 is an enlarged plan view of one corner

2

of my flask, showing an improved hinging and sealing means for the abutting ends of a pair of side walls.

Figure 3 is a greatly enlarged vertical section taken along the line 3—3 of Figure 2 and showing the interfitting sections of the abutting ends.

Figure 4 is a greatly enlarged fragmentary horizontal section taken through the latched abutting ends of another corner of the flask.

Figure 5 is a fragmentary end view in perspective of one of the abutting ends shown in Figure 4.

Figure 6 is a fragmentary end view in perspective of the other abutting end shown in Figure 4, and

Figures 7 and 8 are plan views of my flask showing my flask in closed and released positions, respectively.

Referring more particularly to the drawings, it will be seen that a flask formed of two sections 10 and 11 is rectangular in plan. Section 10 consists of a pair of side walls 12 and 13 rigidly secured together at right angles at the corner 14. Section 11 is composed of side walls 15 and 16 secured rigidly together at right angles, at the corner 17.

The abutting ends 20 and 21 of the respective walls 12 and 16 (Figure 2) are sheared off at an angle of 45 degrees so that a strap hinge 22 will permit the side walls to form an angle of 90 degrees. The inclined face of the end 20 has secured thereon a strip of material 23 which is provided at its outer face with alternately disposed grooves 24 and ribs 25. The inclined face of the end 21 has a strip of material 26 secured thereto and the outer face of the material is provided with alternate ribs 27 and grooves 28 interfitting respectively with the grooves and ribs of the strips 23 to seal the corner 29 against the loss of sand. The strips 23 and 26 may be formed of metal, rubber or a composition material.

An auxiliary sealing device is employed at the corner 29 and is in the form of a flat strip of rubber 30 which has one end 31 secured in any approved manner in a vertical groove 32 in the end 21 of the wall 16. The other end 33 is received freely in a vertical groove 34 in the end 20 of the wall 12. The elastic and flexible member 30 is bowed slightly outwardly at the center so that when the walls 12 and 16 are at right angles to each other, the free end 33 of said member will be forced tightly in the groove 34.

The corner 35 (Figure 4) which is diagonally opposite the corner 29 has the free ends 36 and 37 of the respective walls 13 and 15 in abutting relation when the flask is closed. The end 36

has an inclined face 36a protected by a wear plate 38 which has the inner beveled edge 39 fitting into a V-shaped groove 40 at the outer edge of a wear plate 41 secured by screws 42 to the outer face of the end 37 of the wall 15. Screws 43 fasten a plate 44 and a block 45 triangular in cross section to the end 36 of the wall 13.

As shown in Figures 4, 5 and 6, the inner faces of the block 45 is provided with alternately arranged ribs 50 and grooves 51. Likewise, the plate 41 on the end 37 of the wall 15 has alternately disposed grooves 52 and ribs 53 interfitting with the respective ribs 50 and grooves 51 on the block 45 when the ends 36 and 37 of the respective walls 13 and 15 are in closed position. This structure provides rigidity, as well as preventing up and down movements between the sections.

The ends 36 and 37 are retained in closed or open position by a combined latching device and a toggle lever. For this purpose, a plate 55 (Figures 1 and 5) is secured at 56 to the outer face of the wall 15. The outer free end of said plate is provided with spaced bearings 57 for a pin 58 upon which is mounted an enlarged end 59 of an arm 60. The bearings 57 are located directly in front of the plate 38. A toggle lever 61 hinged on a pin 62 carried by ears 63 fixed to the wall 13. The inner end of the lever is U-shaped with the legs of the U-shaped member spanning the outer end 64 of the arm 60. The outer end is in the form of a bearing receiving a pin 65 carried by the legs of the U-shaped member. A handle 64 provided with a hand grip 67 extends rigidly from the right portion of the U-shaped member.

The walls 12 and 15 have V-shaped pins 70 depending in integral formation from V-shaped sockets 71 attached by screws to the outer faces of said walls. The pins are adapted to be received by sockets secured to pattern boards (not shown) as is well known.

The upper and lower edges of the walls 12 and 15 are reinforced by metal plates 72. The side walls 13 and 16 have secured to the upper and lower edges metal wear plates 73. These plates 45 protect those portions of the flask against wear where they come into contact with other instrumentalities employed in connection with flasks.

The operation of my device will be obvious from the description supra. The flask 10 is shown in 50 closed position in Figures 1 and 7. In this condition, the arm 60 and the toggle 61 are in close relation with the end 36 of the wall 13. At this time, the complementary grooves and ribs of the strips 23 and 26 are in interfitted relation and 55 this is also true of the complementary ribs and grooves on the respective abutting ends of the walls 13 and 15. The elastic and protective strip 30, Figure 2, is in sealing position for the corner 29.

After the usual operations have been completed in the flask, the lever 61 is swung outwardly to the position shown in Figure 8, whence the rigid connections between the ends 12-16 and the ends 60 36-37 are broken so that the walls of the flask may be spread apart sufficiently to remove the

flask. It must be borne in mind that while the lever 61 and the arm 60 release the ends 36 and 37, the ends are retained in a cooperative relationship so that they may be restored readily to their latched position by the return of the lever 61 as shown in Figure 7.

I claim:

1. A snap flask comprising a pair of side walls rigidly secured together and extended at right angles to each other to form an L-shaped member, a second pair of side walls rigidly secured together to form an L-shaped member, a hinge joining an end of one L-shaped member with an end of the other L-shaped member, means releasably connecting the remaining ends of said L-shaped members in abutting relation, each wall adjacent the hinge having a vertical slot formed therein inwardly of the hinge and extending the full height of said walls and an elastic flexible strip of substantial thickness having one edge secured in one of the slots, the other edge of said strip being freely received in the other slot, said strips extending the full length of said slots.

2. A snap flask comprising a pair of side walls rigidly connected together and extended at right angles to each other to form an L-shaped member, a second pair of side walls rigidly secured together to form an L-shaped member, a hinge joining an end of one L-shaped member with an end of the other L-shaped member, means releasably connecting the remaining ends of said L-shaped members in abutting relation, the hinged ends and releasable ends of the L-shaped members having ribs and grooves for interfitting engagement, each wall adjacent the hinge having a vertical slot formed therein inwardly of the hinge and extending the full height of said walls, an elastic flexible strip of substantial thickness having one edge secured in one of the slots, the other edge of said strip being freely received in the other slot, said strip extending the full length of said slots.

ANTHONY J. KLIMEK.
